GRID CASTING MACHINE

Alvy C. Yerkey, deceased, late of Chicago, Ill., by
 Anna C. Yerkey, executrix, Maywood, Ill.

Application April 22, 1940, Serial No. 331,052

4 Claims. (Cl. 22—77)

This invention relates to a grid casting machine and the like.

An object of the invention is to provide a semi-automatic grid casting machine by which molds may be filled and removed by a single operator, the filling of the molds being automatic. A further object is to provide a grid casting machine of simple and effective construction by which molds may be automatically filled and the grids removed by an operator, the mold support being shaken or agitated at predetermined intervals. A further object is to provide a grid casting machine equipped with a rotatable table and with means for disconnecting the same to render the same stationary. A further object is to provide a machine which may be used as a grid casting machine or, alternatively, as a burning table, a change of spur gearing being made possible for the reduction of the speed of the table for the burning operation. Other specific objects and advantages will appear as the specification proceeds.

The invention is illustrated in a preferred embodiment, by the accompanying drawing, in which—

Figure 1 represents a side view in elevation of apparatus embodying my invention; Fig. 2, a broken detail and part sectional view showing the clutch structure employed; and Fig. 3, a top plan broken and sectional view of the clutch handle structure employed.

In the illustration given, A designates a supporting frame consisting of a plurality of standards or legs 10. Supported upon the top of the legs 10 is a circular anti-friction bearing plate 11. Plate 11 supports a ball race 12 equipped with anti-friction balls. Upon the bearings 12 is supported a circular plate 13 fixed to the mold table 14. A shaft 15 supported centrally upon the circular table 14 supports a grid rack or platform 16 upon which finished grids may be stacked. The table 14 is provided on its underside and at spaced distances with a number of racks 17. The teeth of the racks 17 extend downwardly and are adapted to be engaged by a roller 18 supported upon a bracket 19 on frame 10. The engagement of the roller 18 with the rack teeth produces a vibration or jarring of the table at desired intervals.

Any suitable means for rotating the table 14 may be employed. In the illustration given, there is provided a vertical drive shaft 20 which is fixed to the table 14 and which extends downwardly through the guides 21 and 22, the lower end of the shaft being supported within the cross

beam 23 carried by the frame 10. Shaft 20 is provided with a pin 24, securing it to a plate member 25, the plate being supported upon the anti-friction bearing members 26. At its lower end, the shaft 20 is equipped with a worm gear 27.

The source of power is the motor 28 supported upon the frame and driving a pulley 29 equipped with a safety flange. The belt 30 leads from pulley 29 to a second pulley 31. Pulley 31, which is fixed to a shaft 32, drives a gear 33, also fixed to shaft 32. Gear 33 meshes with gear 34, which is fixed to drive shaft 35. The shaft 35 is supported by the frame by means of the straps 36 which are shown more clearly in Fig. 2. Shaft 35 is equipped at one end with a pinion 37 which meshes with gear 38 fixed to the worm shaft 39. The worm 40 carried by shaft 39 is adapted to be brought into mesh with the worm gear 27 to rotate the shaft 20.

The worm 40, together with its shaft 39, is supported upon a frame 41 pivotally mounted on shaft 35. Bushings 42 are pressed tight into the swivel and swung in the split bearings 36, allowing the shaft to rotate inside.

The casting 41 is provided with an inwardly extending lever arm 43 to the end of which is secured a clutch rod 44. The upper end of the rod 44 is pivotally connected to the end of a lever 45 pivotally mounted on the shaft 46. The opposite end of the lever 45 is extended to form a handle 47. As shown more clearly in Figs. 1 and 3, the handle lever 47 is equipped with a latch bar 48 equipped with a locking plunger 49 adapted to extend through a recess in handle 47 and in the fixed frame member 50. There are two locking recesses 51 within the frame member 50 adapted to receive the plunger 49. The latch bar 48 is pivotally mounted upon the pivot member 52 and is normally urged into engaging position by the spring 53.

In normal operation, the table 14 supports four or more molds. In the illustration given, a single mold 54 is shown supported upon the table 14. The mold is equipped with the usual locking frame 55 adapted to engage cams (not shown) for maintaining the mold parts in position. At the outer end of the locking frame 55 is a cam extension 56 adapted to engage and control arm 57 mounted upon a pouring device, such as illustrated in Patent No. 2,135,245, which issued November 1, 1938. Thus, when the rotation of the table brings the cam member 56 into engagement with the lever 57, the pouring device operates automatically to fill the mold.

Operation

In the operation of the device, when it is desired to rotate the table 14, the operator releases the latch bar 48 from engagement with one of the recesses 51 and presses the handle bar 47 downwardly so as to swing the clutch rod 44 upwardly. Upward movement of the bar 44 causes the arm 43 to swing upwardly and the pivotally mounted frame 41 to swing downwardly, thus bringing the worm 40 into engagement with the worm gear 27. The latch bar 48 is then released so as to bring the plunger 49 into engagement with one of the locking recesses 51, thus locking the handle in the position in which the worm member 40 is in engagement with the worm gear 27. In this position, the motor drives the pulley 29 and pulley 31. The belt 33 drives the wheel 34 on shaft 35 and through shaft 35, pinion gear 37, spur gear 38, and shaft 39, the worm 40. The worm gear 27 is thus rotated and shaft 20 rotates with it. The table 14 carrying the molds is thus rotated. As each mold is brought into alignment with the pouring control lever 57, the cam carried by the bracket 55 swings the control lever and causes the mold to be automatically filled. In the filling position, or in any other suitable position, the mold is jarred by the engagement of roller 18 with the rack 17, thus causing the molten metal to follow the cavities within the mold. During subsequent rotation of the table 14, the molds are opened and the grids removed, the grids being stacked usually upon the platform 16.

When it is desired to use the table 14 as a burning table, the molds are removed and the spur gears changed so as to reduce the speed of rotation. Thus, a slowly moving table is provided for the burning operation.

In the usual operation, the molds are heated prior to the pouring operation so as to be effective in producing a good flow of the liquid within the cavities.

If desired, a casing wall may be placed around the standards 10 so as to completely enclose the working parts which have been described.

With the relatively wide plates 11 and 13 illustrated, it will be noted that the table 14 may be readily jarred or jolted by the engagement of the roller 18 with one of the racks 17 without interfering with the rotation of the table.

The operation is substantially automatic, only one operator being required for the removal of the castings.

While in the foregoing specification, certain details have been set forth as desirable and for the purpose of illustration, it will be understood that such details may be modified widely without departing from the spirit of the invention.

What is claimed is:

1. A grid casting machine comprising: a frame, a table supporting member carried by said frame, anti-friction bearings supported upon said table supporting member, a table adapted to carry molds supported upon said bearings, a vertical shaft fixed to said table and mounted for rotation, a rack member carried by said table, a roller member carried by said frame and adapted

10 to engage said rack to shake said table when the table is rotated, and means for rotating said vertical shaft.

15 2. A grid casting machine comprising a frame, a table rotatably mounted on said frame, said table being adapted to support a plurality of molds, a member rigidly mounted on said table, a second member rigidly mounted on said frame and adapted to engage first-mentioned member, one of the members being equipped with an irregular surface for engaging the other member when the table is rotated whereby rotation of the table and the engagement of the members produces a shaking of the table.

20 3. A grid casting machine comprising a frame, a table supporting plate carried by said frame, a circular series of anti-friction bearings carried by said plate adjacent the periphery thereof, a table rotatably mounted upon said bearings, said table being arranged to permit vertical reciprocating motion thereof, a vertical shaft fixed to said table and mounted for rotation, means for rotating said vertical shaft, a roller member, a member equipped with an irregular surface for engaging the roller member, one of said members being fixedly mounted on the frame and the other member being fixedly mounted on the table with the irregular surface of the second member in engagement with the roller member whereby rotation of the table and the engagement of the members produces a shaking of the table.

25 4. A grid casting machine comprising a frame, a table rotatably mounted on said frame, said table being adapted to support a plurality of molds, means for rotating said table, a rack member, a roller member, one of said members being rigidly mounted on said table and the other of said members being rigidly mounted on said frame with the irregular surface of the rack member being adapted to be brought into engagement with the roller member upon rotation of the table whereby rotation of the table and the engagement of the members produces a shaking of the table.

ANNA C. YERKEY,
Executrix of the Estate of Alvy C. Yerkey,
Deceased.
